UNITED STATES PATENT OFFICE.

MORTIMER B. MILLS, OF CHICAGO, ILLINOIS, ASSIGNOR TO THE MILLS IMPROVED PNEUMATIC BRAKE COMPANY, OF SAME PLACE.

AIR-PRESSURE APPARATUS FOR CAR-BRAKES.

SPECIFICATION forming part of Letters Patent No. 497,475, dated May 16, 1893.

Application filed April 25, 1892. Serial No. 430,571. (No model.)

To all whom it may concern:

Be it known that I, MORTIMER B. MILLS, a citizen of the United States, residing at Chicago, in the county of Cook and State of Illinois, have invented a new and useful Improvement in Air-Pressure Apparatus for Car-Brakes, of which the following is a specification.

My invention relates to an improved apparatus for use in applying the brakes of cars, at the will of the operator, by converting the energy of the car in motion into air-pressure for setting the brakes.

The object of my invention is to provide especially effective mechanism for exerting the power of the moving car upon the air-pressure generating mechanism whence it shall be applied directly to setting the brakes; and to this end my invention consists in the general construction of my improved apparatus, and it also consists in details of construction and combinations of parts.

In the accompanying drawings—Figure 1 is a plan view of my improved air-compressing apparatus applied to an axle. Fig. 2 is a section of the same taken on the line 2 of Fig. 1 and viewed in the direction of the arrow. Fig. 3 is a section taken on the line 3 of Fig. 1 and viewed in the direction of the arrow. Fig. 4 is a section taken on the line 4 of Fig. 1, viewed in the direction of the arrow and enlarged. Fig. 5 is a diagrammatic plan view of the entire apparatus as connected to the brake-mechanism of a car.

A (Fig. 3) represents the base-portion of a car, which may be a street-car, for which my improvement is particularly designed, or a railway car.

On a rotary axle B of the car is secured, to rotate with it, an eccentric C loosely surrounded by its strap C' provided with a guide-pin r extending transversely of the strap from a boss r' on one side of its periphery.

E is a slotted extension of the piston-rod E' of an air-pump F, supported in horizontal position at a right-angle to the axle B below the car, as by being flexibly or loosely suspended through the medium of links q, and connected with bifurcated arms p (Fig. 1) fastened to opposite sides of the pump-cylinder and thence extending to and embracing the axle B on which they are rigidly supported at their

ends through the medium of collars o surrounding the axle and within which it rotates. The slotted extension E of the piston-rod embraces the axle B and guide-pin r, on one side of the eccentric C; and it carries at one side a suitable stop, or dog G pivoted to one side of the piston-rod extension near its free end, being adapted to be thrown with its free end into and out of engagement with the guide-pin r. The means for controlling the adjustment of the dog G may be a chain n connected with it near its free end from a bell-crank lever m conveniently accessible to the operator on the car. The dog may tend only by its gravity to engage the guide-pin r, or it may be assisted in its tendency by a spring n', indicated by a dotted line representation in Fig. 3, being connected at one end with an ear v on the dog and at its opposite end with an eye v' on the piston-rod extension E.

From the foregoing the operation of the apparatus, as thus far described, will be understood to be as follows: Normally the dog G is raised out of engagement with the pin r, and then as the axle B rotates in the motion of the car the eccentric C revolves and moves its strap C' with the guide-pin r back and forth in the slot of the piston-rod extension E, without working the piston. When, however, the operator desires to apply the brakes, he manipulates the lever m in a manner to permit the dog G to assume the position in which it is illustrated of engaging the pin r, whereby the action of the eccentric reciprocates the extension E and with it the piston-rod E', whereby the piston E' is reciprocated back and forth in the cylinder of the pump. It is preferred that each stroke of the piston shall draw air into the cylinder at one side and force the previously admitted air out under pressure at the other side of the piston into a cylinder D and against a piston therein, the rod l of which is connected with the lever H of any ordinary or suitable brake-system, such as the one represented in Fig. 5. As will be seen, the motion of the car is transformed into air-pressure, which is immediately directed against and forces out the piston of the cylinder D which sets the brakes just at the time it is desired to stop the car and in a man-

ner to promote the stoppage by the resistance of working the pump. The air-pressure holds the brakes set till the dog G is raised by properly turning the lever *m*, when the weight of 5 the brake-shoes (which may be assisted by the releasing-springs usually provided) causes them to drop from their positions of bearing against the wheels after the movement of the lever *m* by its connection *t* with the handle *f'* 10 of an ordinary two-way valve *f*, has turned the valve to open to the outer air the feed-pipe to the cylinder D; and, as will be understood, turning the lever *m* to engage the dog G with the stop *r* turns the valve *f* to close 15 the passage. The position of the valve *f* is indicated by the reference-letter *w* in Fig. 5.

To produce the desired air-compression with each stroke of the piston E', I provide at opposite ends of the cylinder of the air-pump F 20 double check-valve devices K and K' of the construction illustrated in Fig. 4, and each comprising two connected chambers *k* and *k'*, divided by a diaphragm *k*² seating a downwardly closing check-valve *i* between the two 25 chambers and near the outlet-end *i'* of the device of the chamber, *k'* having a combined inlet and outlet opening *g*², near which is seated, over an air-inlet *g'*, a downwardly closing valve *g*. The devices K and K' are connected, each at its opening *g*², respectively with the opposite ends of the pump-cylinder, and from their openings *i'* lead the conducting pipes *i*² and *i*³, which unite at *x*, whence the pipe *i*³ continues into the compressed-air 30 cylinder D to permit the pump to force the air against the piston therein.

By the foregoing construction, as will be ob-

served, the power of the rotating axle B which is employed to work the air-pressure to set the brakes is immediately resisted from the 40 beginning of the operation by the air-pressure mechanism, thereby employing throughout the operation the inertia of the moving car to bring it to a standstill.

The details of the valves on the pump and 45 of other parts of my improved apparatus may be variously departed from without thereby departing from my invention. Hence I do not wish to be understood as limiting my invention thereto.

What I claim as new, and desire to secure by Letters Patent, is—

In combination with a car and its brake-system, air-pressure apparatus for operating the brakes, having an eccentric C on an axle 55 D with its surrounding strap C' provided with a guide-pin *r*, an air-pump F having its cylinder flexibly suspended from the car-body and connected at opposite sides with corresponding ends of arms *p*, the opposite ends of 60 which are firmly fastened to collars *o* surrounding the axle, and the piston-rod E' of the pump being provided with the slotted extension E embracing the said axle and guide-pin and carrying a pivotal dog G, and a suitable lever connected with the dog for adjusting it into and out of engagement with the guide-pin, substantially as and for the purpose set forth.

MORTIMER B. MILLS.
